STAPLING MACHINE

Harold Matthews, James Henry Warnsties, Edward Arthurs, and William Carl Wilkinson, Calipatria, Calif., assignors of one-fourth to San Diego Fruit and Produce Company, San Diego, Calif., a corporation of California

Application April 25, 1933, Serial No. 667,806

9 Claims. (Cl. 1—3)

Our invention relates to stapling machines and the objects of my invention are:

First, to provide a machine of this class which is particularly adapted to secure one end of a staple to a member such as a box, basket, or hamper lid whereby the remaining end of the staple is extended for subsequent securing of the lid to a complementary device;

Second, to provide a machine of this class incorporating a novel means which automatically feeds the staples one at a time into position for delivery;

Third, to provide a machine of this class which is adapted to be connected to the discharging means of a staple forming machine;

Fourth, to provide a machine of this class which may be arranged in the form of a removable fitting attachable to a conventional punch and die machine; and,

Fifth, to provide on the whole a novelly constructed stapling machine which is particularly simple of construction and of maintenance, durable, efficient in its action and which does not readily deteriorate or get out of order.

With these and other objects in view, as will appear hereinafter, our invention consists of certain novel features of construction, combination and arrangement of parts and portions as will be hereinafter described in detail and particularly set forth in the appended claims, reference being had to the accompanying drawing and to the characters of reference thereon, which form a part of this application in which:

Figure 1 is a partial sectional, partial plan view of the stapling machine through 1—1 of Fig. 2; Fig. 2 is a partial sectional, partial elevational view thereof through 2—2 of Fig. 1; Fig. 3 is a sectional view thereof taken in part through 3—3 of Fig. 1.

Similar characters of reference refer to similar parts and portions throughout the several views of the drawing.

Support and guide means 1, plunger blade 2, bearing 3, shaft 4, staple delivery wheels 5, tension spring 6, staple feeding arm 7, bracket 8, retainer 9 and table 10 constitute the principal parts and portions of the stapling machine.

The herein described machine is particularly suited for staples which are substantially U-shaped in form, comprising a relatively long, straight cross portion S1 with slightly inturned but straight prongs S2 which are pointed at their extremities.

A support and guide means 1 is provided which comprises a pair of vertically disposed plate mem-

bers 1a and 1b which define a vertically extending slot 1c. The plate member 1a is removable while the plate member 1b is provided with a foot or bracket portion 1d which is attached to any suitable support such as the bed of a punch and die machine. The foot 1d spaces the plate members upwardly from said bed.

Vertically slidable in the slot 1c is a plunger blade 2. The plunger and its slot have approximately the thickness of the staple S. The plunger blade protrudes from the upper end of the support and guide means 1 and is vertically reciprocated by any suitable mechanism such as the plunger or the like member of a punch machine, not shown.

The plate member 1b is provided with a laterally extending opening 1e which intersects the slot. The opening extends the length of the cross portion S1 of the staple and is provided with downwardly extending enlargements 1f at its extremities to receive the legs S2 of the staple as shown best in Fig. 2. Between the enlarged ends 1f of the opening 1e and immediately below its central portion, the plate member 1b is provided with an outwardly extending bearing 3 which is slotted at its central portion. The bearing 3 extends horizontally and in parallel disposed relation with the plane of the punch blade 2.

Journalized in the bearing 3 is a shaft 4. A staple delivery wheel 5 is secured to each end of the shaft 4. Each wheel protrudes into the enlarged portions 1f of the slot 1e and is provided with an arm portion 5a which extends underneath the plunger blade, there being provided a corresponding slot 1g in the plate member 1b. A tension spring 6 is provided which engages the shaft 4 in such a manner as to shift the arms 5a upwardly until limited by the upper extremities of the slots 1g, or engagement with the under edge of the plunger blade 2.

When the plunger blade 2 is raised and the arms engage the upper ends of the slots 1g, the arms define with the body of the wheels 5 V-shaped notches 5b having their apexes directed downwardly and directly under the plunger blade 2. The notches 5b together support a staple S by its cross portion S1. When so positioned the staple is engageable by the plunger blade 2 as shown best in Fig. 3. The engaging under edge of the blade 2 is preferably channeled to conform to the curvature of the section of the staple, but it is relieved opposite the arms 5a as indicated by 2a so as to be engaged thereby when the staple is absent.

When the arms 5a are positioned in their ex-

treme upwardly directed positions, the forward edges of the wheels 5 have rudimentary hooks 5c adapted to engage and carry one staple by its cross portion. When the arms 5a are depressed by 5 the action of the plunger blade the wheels rotate to lift the hooks 5c and a staple carried thereby until the staple is lifted over the center of the wheels and may slide downwardly thereon until stopped by the side of the blade 2 as shown by 10 dotted lines in Fig. 3.

When the hooks 5c are in their forward position they are in receptive relation, that is flush with the upper side of an inclined staple feeding arm 7. The arm 7, which is shown fragmentary 15 is smooth surfaced and sufficiently wide to fit snugly but slidably between the legs S2 of the staples as shown in Fig. 1. The staples feed downwardly by gravity on the arm.

Suitably supported so as to extend over the 20 feeding arm 7 is a bracket 8 which supports a retainer 9. The retainer 9 is in the form of a leaf spring which comprises a center finger 9a and side fingers 9b. The center finger 9a extends to the end staple resting on the hooks 5c, while 25 the side fingers 9b extend only to the adjacent staple. Thus the center finger raises partway with movement of the wheels 5 retaining the staple against accidental dislodgment from the hooks 5c while the side fingers prevent the remaining staples from being disturbed. The portions of the wheels 5 following the hooks 5c form stops which are arcuate having radii equal to the extremities of the hooks 5c whereby the 30 staples are held from advancing until the hooks 35 return to position.

Disposed under the extended portion of the support and guide means 1 is an arcuate or otherwise shaped table 10. In this case the table 40 is shown as arcuate to receive a circular, wooden basket or hamper lid, shown fragmentarily in Fig. 2, into the periphery of which it is desired to secure by a plurality of staples. The inner edge of the table is provided with an arcuate ridge 10a to aid in positioning the lid as 45 shown best in Figs. 1 and 2. Directly below the outer end of the slot 1c the table 10 is provided with a groove 10b arranged to engage the extremity of a prong S so as to curl it under and into a lid as shown best in Fig. 2.

50 By reason of the inturned nature of the prongs S2 there is a tendency for the staples to shift rearwardly as they are secured to the lid. For this reason the rear lower extremity of the slot 1c is recessed backwardly from its normal plane 55 as indicated by 1h in Fig. 2. The table 10 is set upwardly from the bed B so that the protruding end and its prong is undamaged when the other end is being acted upon.

60 Operation of the stapling machine is as follows:

With one staple positioned in the V-shaped notches 5b, another resting on the hooks 5c, and the plunger blade 2 moving downwardly into engagement with the first staple as shown in Fig. 3, 65 the blade causes the wheels to rotate counter clockwise against the action of the spring 6 so that the arms 5a descend until they clear the path of the blade. Before this, the prongs S2 have entered the uninterrupted lower portion of the slot 1e and are held thereby. Further movement 70 causes the prongs to protrude from the bottom of the slot, the one prong engaging the lid, the other prong being engaged by the recessed portion 1h and retaining the staple in position.

During this movement, the next staple is carried upwardly and over the wheels 5 so as to rest against the side of the blade 2. Upon raising of the blade, the wheels follow the same by action of the spring, rotating clockwise until limited by the slots 1g. When the blade 2 raises slightly farther, the next staple slides to the apexes of the notches 5b so as to be engageable by the blade on its next downward movement.

Though we have shown and described a certain construction, combination, and arrangement of parts and portions, we do not wish to be limited to the particular construction, combination and arrangement set forth, but desire to include in the scope of our invention the construction, combination and arrangement substantially as set forth in the appended claims.

Having thus described our invention, what we claim as new and desire to include by Letters Patent is:

1. In a stapling machine, a guide, a plunger blade slidably mounted therein, a staple delivery means mounted at the side of the guide, said guide being apertured to expose the plunger blade, said delivery means including a positioning element adapted to support a staple in the path of said plunger blade, an element arranged to carry a staple, and an element engageable with said plunger blade for shifting said delivery means whereby said positioning element is moved clear of said plunger blade and said carrying element transfers a staple into receptive relation with said positioning element.

2. In a stapling machine, a guide, a plunger blade slidably mounted therein, a staple delivery means mounted at the side of the guide, said guide being apertured to expose the plunger blade, said delivery means including a positioning element adapted to support a staple in the path of said plunger blade, an element arranged to carry a staple, an element engageable with said plunger blade for shifting said delivery means whereby said positioning element is moved clear of said plunger blade and said carrying element transfers a staple into receptive relation with said positioning element, and a staple feeding means arranged to support a plurality of staples in a series whereby said carrying element may engage the end staple of the series.

3. In a stapling machine, a plunger blade, a guide for said blade apertured at one side to admit a staple whereby said staple may be inserted in the path of the blade, a pair of delivery wheels mounted at the side of the guide and including positioning elements extending underneath the plunger blade adapted to support a staple in co-active relation with said blade, and carrying elements arranged to transfer a staple to the side of said blade, said blade engageable with said wheels to shift said positioning elements clear and simultaneously actuate said carrying elements, whereby upon subsequent raising of said blade, said positioning means receives and positions the next staple.

4. In a stapling machine, a plunger blade, a die means coacting therewith, a staple feeding means, a pair of staple delivery members extending under the plunger blade and adapted to be shifted thereby on its working stroke, yieldable means for returning said delivery members whereby they follow the plunger blade on its return stroke, stops for limiting the movement of said delivery members whereby said blade may rise thereabove, staple transferring means formed by said delivery members arranged to carry staples

one at a time from said feeding means to said plunger upon operation of said delivery members in response to said plunger blade, and positioning means also formed by said delivery members oper- 5 able when said delivery members are in their limited positions to dispose a staple in the path of said plunger blade.

5. In a stapling machine, the combination with a coacting plunger blade and die means adapted 10 to clinch a staple, of a staple feeding means terminating in spaced relation with the plunger blade, a delivery mechanism engaged by said plunger blade to withdraw a staple from said feeding means and deposit the same in proximity to 15 said blade whereby, upon its subsequent movement, the blade both engages said staple to act thereon and operates said delivery mechanism to position the next staple.

6. In a stapling machine for initially U-shaped 20 staples having a pair of prongs converging towards their extremities, a plunger blade, a guide therefor, an anvil, said plunger blade and guide adapted to receive U-shaped, converging pronged 25 staple and direct one of the prongs into engagement with said anvil, said guide embracing the other prong of the staple to maintain the staple in position, and relieved to permit longitudinal movement of the staple whereby the other prong may move along its axis and penetrate an object 30 disposed on the anvil.

7. In a stapling machine for initially U-shaped 35 staples having a pair of prongs converging towards their extremities, a plunger blade, a guide therefor, an anvil, said plunger blade and guide adapted to receive a U-shaped, converging pronged 40 staple and direct one of the prongs into engagement with said anvil, said guide embracing the other prong of the staple to maintain the staple in position, and relieved to permit longitudinal movement of the staple whereby the other prong may move along its axis and penetrate an object 45 disposed on the anvil, a staple feeding means, the inturned or converging legs of the staples embracing said staple feeding means to form sliding connections therewith, and a delivery means adapted to position a staple one at a time into co-operative relation with said plunger 50 blade.

8. In a stapling machine for initially U-shaped staples having a pair of prongs converging towards their extremities, a plunger blade, a guide therefor, an anvil, said plunger blade and guide adapted to receive a U-shaped, converging pronged 55 staple and direct one of the prongs into engagement with said anvil, said guide embracing the other prong of the staple to maintain the staple in position, and relieved to permit longitudinal movement of the staple whereby the other prong may move along its axis and penetrate an object 60 disposed on the anvil, a staple feeding means, the inturned or converging legs of the staples embracing said staple feeding means to form sliding connections therewith, and a delivery mechanism actuated by movement of the plunger blade for transferring staples one at a time from said feeding means into coactive relation with said plunger blade. 65

9. In a stapling machine for initially U-shaped staples having a pair of prongs converging towards their extremities, a plunger blade, a guide therefor, an anvil, said plunger blade and guide adapted to receive a U-shaped, converging pronged 70 staple and direct one of the prongs into engagement with said anvil, said guide embracing the other prong of the staple to maintain the staple in position, and relieved to permit longitudinal movement of the staple whereby the other prong may move along its axis and penetrate an object 75 disposed on the anvil, a staple feeding means, the inturned or converging legs of the staples embracing said staple feeding means to form sliding connections therewith, and a delivery mechanism including an actuating and staple 80 positioning element extending between the plunger blade and the anvil and adapted to be engaged by and shifted clear of the plunger blade, and means actuated by movement of said element for transferring a staple from said feeding means to 85 a position between said element and said plunger blade whereby subsequent action of the plunger blade shifts said element from its path and carries the staple to the anvil. 90
